(57) **CLAIM**

The ornamental design for an orthopedic device, as shown and described.

DESCRIPTION

FIG. 1 is a front perspective view of a lower assembly of an orthopedic device, showing our design.

FIG. 2 is a front elevational view of the lower assembly of FIG. 1.

FIG. 3 is a first side elevational view of the lower assembly of FIG. 1; and,

FIG. 4 is a second side elevational view of the lower assembly of FIG. 1.

The broken lines are included for the purpose of illustrating environmental structure and form no part of the claimed design.
